J. H. ANANSON.
PAPER HOLDER
APPLICATION FILED APR. 4, 1917:

1,241,897.

Patented Oct. 2, 1917.

UNITED STATES PATENT OFFICE.

JOHN H. ANANSON, OF STIRLING, NEW JERSEY.

PAPER-HOLDER.

1,241,897.

Specification of Letters Patent.

Patented Oct. 2, 1917.

Application filed April 4, 1917. Serial No. 959,819.

To all whom it may concern:

Be it known that I, JOHN H. ANANSON, a citizen of the United States, and a resident of Stirling, county of Morris, and State of New Jersey, United States of America, have invented certain new and useful Improvements in Paper-Holders, of which the following is a specification, reference being had to the accompanying drawings, forming 10 a part thereof.

My invention relates to holders or cabinets for dispensing sheets of paper or the like.

One object of my invention is to provide a 15 simple and durable paper holder comprising a plurality of compartments and particularly adapted for simultaneously delivering a plurality of superposed sheets.

In making typewritten copies it has usually been necessary to assemble a first sheet 20 together with one or more copy sheets, and interposed carbon sheets. This necessarily consumes considerable time and it has been my aim to provide a holder which is particularly adapted to deliver a plurality of superposed sheets such as, for example, a first sheet of typewriter paper, a carbon sheet and a second sheet ready for use.

Another object of my invention is to provide 30 a holder having a single means for effecting the delivery of the superposed sheets, and means for guiding these sheets into accurate register as they are delivered from the holder, in such a way that they 35 may be handled as a single sheet.

In order that my invention may be thoroughly understood, I will now proceed to describe the same in the following specification and then point out the novel features thereof in appended claims.

Referring to the drawings:

Figure 1 is a longitudinal section of a holder arranged and constructed in accordance with my invention and constituting an 45 embodiment thereof.

Fig. 2 is a partial plan view of the same holder with the casing broken away at one point to disclose the driving mechanism for the rolls.

Fig. 3 is a partial end elevation showing 50 particularly the gearing by which the actuating rollers are driven.

A detail of the structure which supports the rolls and gears is shown on a larger 55 scale in Fig. 4.

A modification of my invention is shown in Fig. 5 which corresponds to a portion of Fig. 3.

Fig. 6 is a detail view showing a modified arrangement of the gears for driving the 60 rolls without interfering with their adjustment.

Another slightly modified form of gearing is shown in the sectional detail view 65 of Fig. 7.

Special reference may first be had to Figs. 1 to 4 inclusive, in which 10 designates the body of the holder which has the form of a rectangular box open at the delivery end and having a closed end 11 which is inclined 70 for the purpose hereinafter explained. The interior of the box is divided into compartments 12, 13 and 14 by partitions 15 and 16. The delivery chute 17 is hinge-connected at 75 18 to one edge of the body or box 10 and acts like a lid, being provided with a lateral projection or lug 19 which is engaged by a latch 20 when the chute is in operative position as shown in Fig. 1.

The chute has partitions 21 and 22 which 80 form continuations of the partitions 15 and 16 respectively. The bottom wall of the chute which is designated 23 is provided with a hump near the hinge 18 and the partitions 21 and 22 are provided with correspondingly located humps 24.

The side walls of the holder or box are provided with L-shaped slots 25 in which 85 axles 26 of a plurality of rollers 27 are disposed.

Each of the rollers is preferably made of soft rubber or the like and may be provided with longitudinal ribs as clearly shown in Figs. 1 and 2. A gear wheel 28 is secured to the axle 26 of each roller near its respective ends. Adjacent to the gear wheels on the axles 26 are bearing blocks 30 which are mounted to slide in guideways 31 of a bearing bracket 29. Springs 32 press downwardly on each of the blocks 30 thereby 100 forcing the rollers 27 against the paper or whatever is contained in the compartments of the holder.

Idler gears 33 are rotatively mounted on adjustable blocks 34 which are mounted in 105 guideways 35 of the bracket 29.

The bearing bracket structure may be formed in any suitable manner but I prefer to make it from sheet metal by stamping or pressing. The structure is composed of two 110

parts adapted to be mounted on opposite sides of the holder and preferably interconnected by a plate or strap 26.

The bearing brackets are alike and each of them comprises as shown in Fig. 4, a plate 37 having slots 38 through which the pivot pins 39 of the gears 33 extend and slot 40 through which the roller axles 26 extend.

The strap 36 supports the bearing bracket structure and rests upon the top of the body of the box as shown in Fig. 2.

The plate 37 of the bearing brackets is spaced from the sides of the box by webs 41.

Springs 42 press the gears 33 into mesh with adjacent pairs of gear wheels 28 as clearly shown in Fig. 3, the arrangement of parts being such that when one of the roller axles is turned, as for example, by means of a handle 44, the rollers are concurrently driven.

The springs 42 hold the idler gears 33 in mesh with the gears 28 at all times independently of the spacing of the gears.

In Fig. 7 I have shown a modification in which the rollers 27 are rotatively mounted on fixed axes and are connected by suitable gearing corresponding to that shown in Fig. 3, for example, although the idler gears may also be fixed in this instance.

Instead of the partition plates 15 and 16, I provide in this arrangement floating partition plates 46, 47, and 48 of which the plate 48 constitutes a movable bottom plate. Each of the plates is provided with lateral lugs or projections 49 which extend through suitable slots 50 in the side walls of the holder. Springs 51 are mounted to press upwardly upon the plates 46, 47 and 48, the arrangement of parts being such that the plates are pressed against the rolls when there is no paper in the holder, or when the paper is introduced it is held in contact with the rolls at all times.

In Fig. 5 I have shown another modification in which the rolls are provided with pulleys or sheaves 52 which are interconnected by electric belts 53. By this means the rolls are all driven concurrently and may be held in contact with the paper at all times by suitable springs as shown in Fig. 3.

The rollers may be mounted to swing on arms or trunnions 54 as shown in Fig. 6 instead of being arranged to move in a straight line. In this case each roll may be driven by a fixed idler gear 56 mounted at the pivotal center of the arms or trunnions 54. A spiral or other suitable spring 55 presses each roll toward the partition or wall below it.

The idler gears may be interconnected by belts, gears or any suitable means such as those illustrated in the previous figures.

In using the holder it is evident that it may be mounted on a sheave on the top of

a typewriter disk or in any suitable position where it can be conveniently reached by the typewriter operator.

The holder will be loaded with at least a sufficient amount of paper and carbon sheets and second sheets for one day's supply. When the paper is introduced the sheets are offset slightly relative to each other as shown in Fig. 1, on account of the inclined formation of the bottom plate 11. This is for the purpose of insuring that the sheets are taken off, one at a time, by the rollers. Furthermore, this insures that the sheets in the upper compartment 12 are slightly more advanced than those in the lower compartments so that they all arrive at the outlet 60 of the chute in proper register.

The humps 24 furthermore serve to hold back the body of the paper and prevent it all coming out together instead of one sheet at a time.

By reason of the L-shaped formation of the slots 25 and the fact that the bearing support constitutes a unitary structure 90 which is mounted on the box or body of the device, the supporting structure, together with the rolls, may all be removed when the chute is swung open on the hinge 18. This provides a convenient method of access to the rolls for cleaning or the like, and also may be employed as a ready means for getting the rolls out of the way to facilitate the filling. When the rolls are forced back in place they rest upon the several piles of paper and the device is ready for use.

Various structural modifications may be effected within the spirit and scope of my invention and I intend only such limitations as are imposed by the appended claims.

What I claim is:

1. A paper holder comprising a rectangular body having an open end, partitions dividing the interior of the body with the walls thereof into compartments adapted to contain sheets of paper, and a tapering chute having a single discharge opening, hinged at the open end of the body and having converging partitions forming continuations of the walls and partitions of the body, said chute being adapted to be opened to introduce paper into the compartments, rolls in the compartments, and means for concurrently actuating the rolls for delivering the paper to the chute sheet by sheet, whereby the sheets are discharged from the single opening of the chute in registering superposed relation.

2. A paper holder comprising a rectangular horizontal body, partitions dividing the interior of the body into compartments adapted to contain sheets of paper, and a tapering chute having a single discharge

- opening and converging partitions forming continuations of the partitions of the body, said chute extending outwardly and downwardly from the body, and means for discharging the paper from the compartments through the single outlet opening of the chute in registering superposed relation.
3. A paper holder comprising a rectangular horizontal body, partitions dividing the interior of the body into compartments adapted to contain sheets of paper, and a tapering chute having a single discharge opening and converging partitions forming continuations of the partitions of the body, said chute being hinge-connected to the body at its open edge and having its bottom wall and partitions formed to retard the movement of the paper therethrough.
4. A paper holder comprising a rectangular horizontal body, partitions dividing the interior of the body into compartments adapted to contain sheets of paper, and a tapering chute having a single discharge opening and converging partitions forming continuations of the partitions of the body, rollers in the compartments for discharging a sheet from each compartment, said chute being hinge-connected to the body and openable to introduce paper into the compartments, the bottom wall and partitions of said chute being formed with humps to hold back the paper in the compartments to insure delivery of a single sheet from each.

In witness whereof, I have hereunto set my hand this 30th day of March, 1917.

JOHN H. ANANSON.
